US00D889524S

(12) United States Design Patent (10) Patent No.: US D889,524 S
(45) Date of Patent: * Jul. 7, 2020

(54) MONITORING APPARATUS

(71) Applicant: IBABY LABS, INC., San Jose, CA (US)

(72) Inventor: Yong Xu, San Jose, CA (US)

() Term: 15 Years

(21) Appl. No.: 29/707,519

(22) Filed: Sep. 28, 2019

Related U.S. Application Data

(62) Division of application No. 35/001,158, filed on Feb. 18, 2016 (U.S. filing date under 35 U.S.C. 384), and having an international filing date of Feb. 18, 2016, now Pat. No. Des. 804,977.
